UNITED STATES PATENT OFFICE

JAMES JACKSON, OF BAKERSFIELD, CALIFORNIA

INCUBATOR

Application filed August 12, 1929. Serial No. 385,176.

The invention relates to improvements in incubators of the general type disclosed in my U. S. Patent No. 1,690,169 of December 2, 1927. In this incubator, a plurality of trays are rotatably mounted for turning the eggs, a dial plate is employed co-operable with pointers to allow uniform turning of the trays, and toothed locking wheels are employed on the shafts of the trays co-operable with keys in locking the trays at any positions to which they may be turned, the dial plate, locking wheels and keys being removable when the time arrives for the eggs to hatch. It is the object of the present invention to provide effective means for locking all of the trays against possible tilting from the time the dial plate, locking wheels and keys are removed, until the hatching period is over.

20 With the foregoing in view, the invention resides in the novel subject matter hereinafter described and claimed, description being accomplished by reference to the accompanying drawings.

25 Fig. 1 is a perspective view of an incubator constructed in accordance with my invention and illustrating the locking bar for the trays in its normal position at which it is supported by the dial plate.

30 Fig. 2 is a perspective view illustrating the incubator conditioned for the hatching period, the locking bar being engaged with the shafts of the trays.

Fig. 3 is a transverse sectional view on line 35 3-3 of Fig. 1.

Fig. 4 is a perspective view of the detached dial plate and the spring fingers thereon for normally holding the locking bar.

In the drawings above briefly described, 40 the numeral 5 denotes a drawer-like structure slidable into and from an incubator case 6, being provided with suitable pulls 7. Slidable within the lower portion of this structure 5, is a water pan 8 having a handle 9. Front 45 and rear trunnions 10-11 respectively, carry sectional egg trays 12 and are rotatably mounted in bearings 13 supported by the front and rear walls 14-15 of the drawer-like structure 5.

50 Contacting with the front side of the wall

14, is a dial plate 16, said dial plate being secured detachably in place by any desired means 17. Removably secured upon the front trunnions 10 of the trays 12, are toothed locking wheels 18 which are co-operable with keys 19 in holding the trays 12 at any positions to which they may be turned, the extent of turning being determined by numbers on the dial plate 16 and pointers 20 on the wheels 18, said pointers being co-operable with said numbers.

All of the construction so far described is substantially the same as that shown in my patent, above mentioned. When the time for hatching of the eggs arrives, the top sections of the trays are removed as shown in Fig. 2, and dial plate 16, wheels 18 and keys 19 are all removed as will be clear from this same view. It is then that the improvement constituting the present invention is used to hold the trays 12 against tilting about their trunnions or shafts.

In the present disclosure, the locking means for the trays consists of a flat bar 21 having notches 22 in its lower edge to engage the trunnions 10 as seen in Fig. 2, said bar having additional notches 23 to engage fixed pins 24 which project forwardly from the wall 14 of the drawer-like structure 5, said pins 24 constituting parts of the means 17 for detachably mounting the dial plate 16. The bar 21 is normally supported by spring clips or the like 25 secured to the rear side of the dial plate 16, so that it will be entirely out of the way, yet will be in readiness for use when it is about time for hatching to start.

It will be seen from the foregoing that simple and inexpensive, yet efficient and desirable provision has been made for holding the trays 12 in proper position during the hatching period. The details disclosed are preferably followed due to their advantageous nature, but within the scope of the invention as claimed, variations may be made.

I claim:—

1. In an incubator embodying a plurality of trays, supporting means for said trays embodying front flat-sided trunnions, locking wheels detachably mounted on said trunnions, means co-acting with said locking

45

100

- wheels for holding the trunnions against rotation when desired, and a dial plate detachably mounted behind said locking wheels and instrumental in properly turning the trays; a single bar having notches to directly receive said trunnions and thereby hold the latter and the trays against rotation during the hatching period, said bar being engageable with said trunnions upon removal of said locking wheels and said dial plate.
10. 2. A structure as specified in claim 1; said dial plate having supports at its rear side by which said bar is normally held.
15. 3. In an incubator, a plurality of trays having front and rear trunnions, the former being flat-sided, front and rear supports having bearings in which said trunnions are rotatably mounted, locking wheels detachably mounted on said front trunnions, means co-
20 acting with said locking wheels in holding the trays after turning thereof, a dial plate behind said locking wheels instrumental in properly turning the trays, and means detachably mounting said dial plate, said means embodying rigid pins projecting forwardly
25 from said front support; a locking bar having openings to engage said rigid pins and additional openings to engage said front trunnions, whereby said bar may be used to hold said trays against turning during the hatching period, after removal of said locking wheels and dial plate.
30. 4. In an incubator embodying rotatable trays having forwardly projecting trunnions, a dial plate instrumental in properly turning the trays, and mounting means for said dial plate embodying forwardly projecting rigid pins; a single locking bar having openings to engage said pins and additional openings
35 to engage said trunnions, thereby holding the trays against rotation during the hatching period.

In testimony whereof I have hereunto affixed my signature.

JAMES JACKSON.
